UNITED STATES PATENT OFFICE.

HENRY A. AMMANN, OF SPOKANE, WASHINGTON.

DESIGN FOR AN OPEN GUIDE FOR TOWEL-RACKS.

48,923.

Specification for Design.

Patented Apr. 25, 1916.

Application filed August 25, 1915. Serial No. 47,340. Term of patent 14 years.

To all whom it may concern:

Be it known that I, HENRY A. AMMANN, a citizen of the United States, residing at Spokane, in the county of Spokane, State of Washington, have invented a new, original, and ornamental Design for an Open Guide for Towel-Racks, of which the following is a specification, reference being had to the accompanying drawing, forming a part thereof.

Figure 1, is a front elevation and Fig. 2, is a side elevation of my new design for an open guide for towel racks.

I claim:—

The ornamental design for an open guide for towel racks, substantially as shown.

HENRY A. AMMANN.

Witnesses:

CARL H. CRAWFORD,
CHAS. W. HAY.
